UNITED STATES PATENT OFFICE.

SAMUEL E. MOSS AND WALTER H. WHITE, OF PORTLAND, OREGON.

COIN-CONTROLLED VENDING APPARATUS.

1,165,271.

Specification of Letters Patent.

Patented Dec. 21, 1915.

Application filed June 7, 1915. Serial No. 32,784.

To all whom it may concern:

Be it known that we, SAMUEL E. MOSS and WALTER H. WHITE, citizens of the United States, and residents of Portland, county of Multnomah, and State of Oregon, have invented certain new and useful Improvements in Coin-Controlled Vending Apparatus, of which the following is a specification.

This invention relates generally to vending devices for bottle contained goods in which the article to be vended is freed by the insertion of a coin in the controlling lock.

The direct object of this invention is to provide a vending apparatus of the character mentioned convenient for delivering bottles of milk to patrons under a C. O. D. system. In other words the milkman would install one of our devices with his customer, and each time a delivery is made, lock the bottle of milk therein. Then when the customer wishes to remove the bottle, he must insert the required coin so as to unlock the device. A rack-like device of this character affords the two-fold advantage of securely locking the bottles of milk from being stolen or taken out of the rack, and at the same time insures prompt payment to the milkman each day.

The construction and features of our invention are more readily described with the aid of the illustrations shown in the accompanying drawings, in which—

Figure 1 is a front elevation of our device showing it in actual use; Fig. 2 is a right side elevation of the same; Fig. 3 is a top view with a part of the device broken away for the purpose of illustrating the interior construction; Fig. 4 is a detail showing a rear elevation of a portion of the back wall of our device, also showing the details of the coin controlled lock; Fig. 5 is a larger scaled horizontal sectional view taken on the line 5—5 of Fig. 4, and Fig. 6 is a detail of the ward of one of the locks, which may be used to open the device, for placing or removing a bottle, independently of the operation of the coin-controlled lock.

The casing *a* is made with a hollow back portion indicated by *b* in Fig. 5. The lower part of the casing is provided with a horizontal floor *c*, and vertical sides *d*. In the drawings, one side of the floor *c* is provided with a raised portion *e*, which provides for the placing of a different sized bottle. Guide flanges *f* and *g* are provided in which the lower ends of the milk bottles *h*, *i* will rest. The casing *a* is adapted to be

bolted to a fixed support, such as the door *j*, by the bolts *k*. In the upper portion of the casing is a chamber *l*. Horizontally movable covers *m* and *n* provided with pendent flanges *m'* and *n'* encompassing the front of the top of the bottles, are hinged on the pintles *m²*, *n²*, respectively. Said covers are furthermore provided with projecting fingers *m³* and *n³* adapted to bear against and compress the flat springs *m⁴* and *n⁴*, when the covers are in their locked position, and such springs serving to throw said covers open when the latter are unlocked. On the outer end of these covers are provided studs *o*, made with notches *o'*, and holes are provided in the front wall of the chamber *l*, for such studs to enter, whenever the covers are placed in their closed position. Pivoted on the pins *p*, *q*, in the chamber *l*, are the latch-plates *p'* and *q'*. These are provided on their forward end with lugs *p²* and *q²*, adapted to enter the notches of the studs *o*, of the covers. A tension coil-spring *r* connects the latch-plates and holds the latter in their normal position. Coin tubes *s* and *t* for coins of different denominations converge into the common tube *u*, which empties directly into the drawer *v*. The latter runs in sideways *v'* under the bottom of the casing, and is normally locked by the lock *v²*, which may be of any convenient make. Said coin tubes *s* and *t* are provided with slots in which the free ends of the latch bars *p* and *q* enter, and the latter normally bar the passage of a coin which has been inserted in either of said tubes. Thrust pins *w* connected by a bar *w'* are adapted to slide in the guide plate *x*, project down through an opening in the tubes and bear directly on the coin placed in said tubes. A lever-arm *y*, normally held upward by a spring *y'* is provided with a slotted-end *y²* in which bears a pin *w²* on the bar *w'*, so that when said lever *y* is depressed, the thrust pins *w* will also be depressed. A push-button *z* forms a convenient means for depressing the lever *y*.

The general operation of this device is as follows: When the milkman places the bottles in the device and the covers *m* and *n* are closed, they will be automatically locked. When it is desired to remove one of the bottles, a coin is inserted in the corresponding tube which coin will then immediately drop to the position in which they are shown in the broken lines in Fig. 5. The push but-

ton z is then depressed, which action will cause the thrust pin w to bear down upon the coin inserted in either coin tube, operating one or both of the latch-plates, and 5 in so doing releasing one or both of the covers controlled by such latch-bars. The action of the flat spring will then throw the released cover open. The milkman, however, releases the covers by the use of a 10 key placed on the pins 2 as shown by the broken outlines 3 in Fig. 5, the bit of the keys being made to conform to the openings in the wards 4. These details being left to 15 the judgment of the manufacturer.

15 We claim:

1. In a device of the character described, in combination with a case provided with a flanged floor, a cover provided with a pendent flange, and hinged so as to be movable 20 in a horizontal plane over and away from the top of a container resting on said floor, a portion at the free end of said cover being provided with a notch; a pivoted spring-controlled latch-bar provided with a lug adapted to enter said notch; a vertical coin tube located above the latch plate, the latter entering the coin tube through a slot in one 25 side thereof and thus normally arresting the drop of the coin deposited in the coin tube, an arm fulcrumed at its outer end, a spring normally holding said arm in horizontal position; a perpendicular finger-piece provided on said arm, and a vertically movable member to which the inner end of said arm 30 is connected, a pendent pin carried by said vertically movable member and arranged
- 35

normally to rest on the coin deposited in said coin tube, whereby the depression of said arm will cause the coin to move the latch-bar aside and disengage the cover. 40

2. In a device of the character described, in combination with a case provided with a flanged floor, a plurality of covers provided with a pendent flange, and hinged so as to be movable in a horizontal plane over and 45 away from the top of a container resting on said floor, a portion at the free end of said covers being provided with a notch; a pivoted spring-controlled latch-bar provided with a lug adapted to enter said notch; a 50 plurality of vertical coin tubes, a pivoted, spring-controlled latch-plate located at one side of each of said coin tubes, entering a slot in one side of the latter and thus adapted to normally arrest the drop of a coin deposited in said coin tubes, said latch-plates provided with a lug at their free ends adapted for entering said notches of said covers; an arm fulcrumed at its outer end, a spring normally holding said arm in horizontal position; a perpendicular finger-piece provided on said arm; and a vertically movable member to which the inner end of said arm is connected, pendent pins carried by 55 said vertically movable member and arranged normally to rest on the coins deposited in said coin tubes, whereby the depression of said arm will cause the coin to move the latch bar aside and disengage the cover. 60
